CLAIM

The ornamental design for a boom extension arm, as shown and described.

DESCRIPTION

FIG. 1 is a perspective view of a boom extension arm in accordance with the present invention;

FIG. 2 is a right side elevational view of the boom extension arm of FIG. 1, the left side elevational view being a mirror image of the right side;

FIG. 3 is a front elevational view of the boom extension arm of FIG. 1;

FIG. 4 is a rear elevational view of the boom extension arm of FIG. 1;

FIG. 5 is a top plan view of the boom extension arm of FIG. 1; and,

FIG. 6 is a bottom plan view of the boom extension arm of FIG. 1.

The broken lines showing of portions of the design and of environment, including end features, central joint portion and display, form no part of the claimed design. The drawings are not to scale.
